UNITED STATES PATENT OFFICE.

DANIEL RICHARD WALLWORK HARDMAN, OF LIVERPOOL, ENGLAND.

SAFETY DEVICE FOR TROLLEY-POLES OF ELECTRIC CARS.

SPECIFICATION forming part of Letters Patent No. 792,985, dated June 20, 1905.

Application filed March 14, 1905. Serial No. 250,090.

To all whom it may concern:

Be it known that I, DANIEL RICHARD WALLWORK HARDMAN, a subject of the King of Great Britain, residing in Liverpool, in the county of Lancaster, England, have invented certain new and useful Improvements in Safety Devices for the Trolley-Poles of Electric Cars, of which the following is a specification.

This invention relates to a safety device which is adapted when the trolley-wheel leaves the overhead trolley-wire to draw down the trolley-pole clear of the overhead construction, but which shall during the ordinary running of the car permit the pole to swivel in either the vertical or horizontal plane and follow the deviations of the trolley-wire. In such devices the cord attached to the trolley-pole is connected to a conical grooved barrel, which is provided with a spring which tends to wind up the cord, and so maintains a tension in the cord sufficient to take up the slack, but not sufficient to pull down the pole in opposition to the trolley-pole springs. Coaxial with this barrel is a spring-drum, the spring of which is normally held wound up and which if released when the drum is connected to the barrel is sufficiently strong to rotate the barrel and pull down the cord. The drum and barrel are normally disconnected; but when the trolley-head leaves the trolley-wire electromagnetic means are energized which first connect the drum to the barrel and then release the drum.

The drum is provided with what is known as a "Geneva stop-motion" to limit the extent to which the drum-spring may be wound up, and the present invention relates to means operated by the locking-piece of the Geneva stop and adapted to control both the action of the drum-holding detent and the current which is used to energize the electromagnetic mechanism in such manner that the circuit of the latter is not closed nor the detent permitted to engage the drum until the drum-spring is fully wound up, the object being to insure that the attendant shall when setting the apparatus fully wind the drum-spring. This construction also secures the following further advantage: As it is impossible for the attendant to set the apparatus with the drum-

spring only partly wound up and as the movement of the locking-piece which insures this does not close the circuit of the current to operate the electromagnetic means except when the drum-spring is fully wound up, the said circuit will be opened as soon as the drum begins to rotate—that is to say, after the operation of the electromagnetic means—so that no more current will be used than is necessary for the purpose.

The invention also relates to further improvements in regard to the pawl which locks the drum to the barrel and to the mode of making the electrical contact.

The invention is illustrated in the accompanying drawings, in which—

Figure I is an elevation, with the casing in section, on the line A A of Fig. II, the trigger-piece 27 and the contact-lever 19 being removed to more clearly show the remaining parts; Fig. II, a plan, with the barrel, the drum, and the springs in section, on the line B B of Fig. I, the contact-lever being omitted; and Fig. III, a fragmentary plan to show the mode of carrying the contact-lever omitted from Fig. II. Fig. IV is a part end elevation showing the mode in which the main detent-lever and the trigger are operated by the electromagnet. Fig. V is a fragmentary section of the main detent and trigger lever. Fig. VI is a part end elevation showing the contact-lever and detent-lever in relation to the cam on the locking-piece of the Geneva stop. Fig. VII is an elevation showing the construction of the pawl and its controlling-spring. Fig. VIII is a fragmentary view of the pawl and spring. Fig. IX is a sectional elevation of the trolley-pole contact, and Fig. X a sectional plan of the contact.

Referring in the first instance to Figs. I, II, and III, 1 is the casing in which the apparatus is inclosed, which casing has a suitable cover, which for the sake of clearness is omitted from the drawings. 2 is the coned barrel round which the trolley-rope 3 is adapted to be coiled as the barrel rotates. 4 is the barrel-spring, one end of which is connected to the barrel and the other end of which is connected to the fixed shaft 5, on which the barrel and drum rotate. The spring 4 is just

sufficiently strong to maintain the trolley-rope taut, but not strong enough to pull the trolley-pole down. 6 is the drum, and 7 the drum-spring, attached at one end to the drum 5 and at the other end to the shaft 5. The drum is rotated till the spring is fully wound up, in which normal position the drum is held by the main detent 8. Normally the barrel is free from the drum. The latter, however, carries a pawl 9, adapted to engage with the teeth 10 on the barrel. The pawl is normally held out of engagement with the teeth by the spring 11 and is provided with a second spring 12, which in all positions except the position 15 in which the drum engages with the detent 8 tends to force the said pawl into engagement with the teeth. When, however, the barrel is fully wound up and in engagement with the detent, a pin 13, fixed to the casing, engages 20 with the spring 12, as shown in Figs. VII and VIII.

The Geneva stop - motion consists of a toothed piece 14, connected to the drum and rotating therewith, and a locking - piece 15, 25 carried on a pin on a lever 16. (See Fig. II.) The lever 16 is prevented from rotating by a holding - bracket 17, attached to the casing. When the drum is rotated to wind up the drum-spring, the locking-piece prevents further rotation when the spring is fully wound up. Attached to the locking - piece and carried on the same pin as the latter is a cam-piece 18, having a flat 18^a, which is adapted when the mainspring is fully wound up to 35 come into the position shown in Fig. VI. The detent 8 and the contact-lever 19 bear on this cam-piece, and in all positions of the cam, except that corresponding with the fully-wound-up position of the drum, the detent 8 40 is held away from engaging with the teeth 20 and the contact-lever is held away, so that the contact 19^a is held clear of the contact 21^a of the terminal 21.

The electromagnet 22, which actuates the 45 detent 8, has one end of its winding connected to 19^a and the other end connected to the terminal 23. The two pole-pieces of this magnet, together with its core and winding, are carried by a bracket 24, of non-magnetic substance, and the detent is fulcrumed on a pin 50 25, carried from the bracket 24, the lower end 8^a of 8 forming an armature of the electromagnet. On the same pin 25 the trigger-lever 26 is carried, its armature 26^a being 55 formed of a U-shaped piece of iron, which passes through clearance-holes in the armature 8^a.

The lever 26 bears against a roller on the long arm 27^a of the trigger 27, the short arm 60 27^b of the trigger bearing against the tail of the pawl 9 when the drum is in normal position. When the electromagnet 22 is energized, it first attracts the armature 26^a of the trigger-lever, which latter then so operates 65 the trigger as to cause the pawl 9 to engage

with the teeth 10 on the barrel 2, thus connecting the drum to the barrel. Immediately afterward the armature 8^a is attracted and the main detent disengaged from the tooth 20, so releasing the drum, whereupon the 70 strong drum-spring rotates the drum, which, being connected by the pawl 9 to the barrel 2, causes the rotation of the latter and winds down the trolley-pole.

It will be seen from the construction described that the apparatus cannot be set in normal position until the drum-spring 7 is fully wound up, as otherwise the flat 18^a on the cam-piece 18 does not come opposite the ends of the detent 8 and the contact-lever 19, as shown in Fig. VI, and until the flat 18^a comes into this position the detent 8 cannot engage with the tooth 20 nor 19^a come into contact with 21^a, so as to complete the circuit through the electromagnet. 75

In order to prevent the possibility of the spring 11 disengaging the pawl 9 from the tooth 10 during the operation of the apparatus, a spring 12, as described, is provided, which forces the pawl into contact with the 80 said teeth. In the normal position of the drum the said pawl of course requires to be free of the teeth, and the spring 12 is therefore rendered inoperative in this position by engagement with a pin 13, as shown in Fig. 95 VIII.

Instead of forming the contact, which closes the circuit of the current which energizes the electromagnet, in the trolley-head itself it is preferable to pivot the trolley-pole near the 100 trolley-head, as shown in Figs. IX and X, where the upper and lower parts of the pole are pivoted on the axis 28, so that the two parts can pivot relatively to one another about this axis. A spiral spring bears against seatings on the adjacent parts of the upper portion 30 and the lower portion 30^a of the pole and normally tends to bring the axes of these two parts into line, in which case the two contact - pieces 31 and 32 engage with each 110 other and complete the circuit of the battery and the electromagnet, the connections being as follows: The terminal 21 is connected to the contact 31. The terminal 23 is connected to one pole of the battery, and the contact 32 to 115 the other pole of the battery.

When the trolley is pressed against the trolley-wire, as shown, the trolley - pole springs cause the two parts of the pole to pivot about the axis 28, whereupon the contacts 31 and 32 are separated. When, however, the trolley leaves the wire, the spiral spring brings the two parts of the trolley-pole into line, the contacts 31 and 32 engage, the circuit is completed, the pawl 9 engaged with one of the teeth 10 by the action of the trigger and trigger-lever, after which the detent 8 is drawn from engagement with the tooth 20, whereupon the drum winds the barrel up, as described. 125

Having now fully described my invention, 130

I declare that what I claim, and desire to secure by Letters Patent, is—

1. In combination: a trolley-pole, a light
spring-controlled barrel connected to the trolley-pole by a rope, a heavy spring-controlled
5 drum, means to connect the drum to the barrel, means to hold the drum wound up, an electromagnetic device to operate the connecting and holding means, a switch controlling
10 the electromagnetic means and adapted to close the magnetic circuit when the trolley-pole is free, a mechanism to limit the winding up of the drum, and means operated by the locking-wheel of the said mechanism which render the electromagnetic device inoperative except
15 when the drum is fully wound up, means to connect the drum to the barrel carried on the drum and normally pressed into operative position by a spring, and a fixed pin which when the drum is in its fully-wound-up position
20 renders the last-mentioned spring inoperative; substantially as described.

described.

2. In combination: a trolley-pole, a light spring-controlled barrel connected to the trolley-pole by a rope, a heavy spring-controlled drum, means to connect the drum to the barrel, means to hold the drum wound up, an electromagnetic device to operate the connecting and holding means, a switch controlling the electromagnetic means and adapted to close the magnetic circuit when the trolley-pole is free, a mechanism to limit the winding up of the drum, and means operated by the locking-wheel of the said mechanism which render the electromagnetic device inoperative except when the drum is fully wound up; substantially as described.

as described.

3. In combination: a trolley-pole, a light spring-controlled barrel connected to the trolley-pole by a rope, a heavy spring-controlled drum, means to connect the drum to the barrel, means to hold the drum wound up, an electromagnetic device to operate the connecting and holding means, a switch controlling the electromagnetic means and adapted to close the magnetic circuit when the trolley-pole is free, a mechanism to limit the winding up of the drum, and means operated by the locking-wheel of the said mechanism which render the drum-holding device and the electromagnetic device inoperative except when the drum is fully wound up; substantially as described.

4. In combination: a trolley-pole, a light spring-controlled barrel connected to the trolley-pole by a rope, a heavy spring-controlled drum, means to hold the drum wound up, an electromagnetic device to operate the connecting and holding means, a switch controlling the electromagnetic means and adapted to close the magnetic circuit when the trolley-pole is free, a mechanism to limit the winding up of the drum, means to connect the drum to the barrel carried on the drum and normally pressed into operative position by a spring, and a fixed pin which when the drum is in its fully-wound-up position renders the last-mentioned spring inoperative; substantially as described.

5. In combination: a trolley-pole, a light
65 spring-controlled barrel connected to the trol-

ley-pole by a rope, a heavy spring-controlled drum, means to hold the drum wound up, an electromagnetic device to operate the connecting and holding means, a switch controlling the electromagnetic means and adapted to 70 close the magnetic circuit when the trolley-pole is free, a mechanism to limit the winding up of the drum, means operated by the locking-wheel of the said mechanism which render the electromagnetic device inoperative except 75 when the drum is fully wound up, means to connect the drum to the barrel carried on the drum and normally pressed into operative position by a spring, and a fixed pin which when the drum is in its fully - wound - up position 80 renders the last-mentioned spring inoperative; substantially as described.

6. In combination: a trolley-pole, a light spring-controlled barrel connected to the trolley-pole by a rope, a heavy spring-controlled drum, means to hold the drum wound up, an electromagnetic device to operate the connecting and holding means, a switch controlling the electromagnetic means and adapted to close the magnetic circuit when the trolley-pole is free; a mechanism to limit the winding up of the drum, means operated by the locking-wheel of the said mechanism which render the drum-holding device and the electromagnetic device inoperative except when the drum is fully wound up, means to connect the drum to the barrel carried on the drum and normally pressed into operative position by a spring, and a fixed pin which when the drum is in its fully-wound-up position renders the last-mentioned spring inoperative; substantially as described. 85 90 95 100

7. In combination with the trolley-pole, the barrel, the drum, the Geneva stop, the barrel-connecting means, the electromagnetic means, and the switch which is closed when the trolley-pole is free: the drum-holding device, consisting of a detent-lever adapted to engage with a tooth on the drum, and a cam on the locking-wheel of the Geneva stop which prevents the engagement of the said detent until the drum is fully wound up; substantially as described. 105 110

8. In combination with the trolley-pole, the barrel, the drum, the Geneva stop, the drum-holding device, the barrel-connecting device, the electromagnetic device, and the switch which is closed when the trolley-pole is free: the lever-controlling contacts in the electromagnetic circuit and a cam on the Geneva stop which keeps the said contact-lever in the off position except when the drum is fully wound up; substantially as described. 115 120

9. In combination with the trolley-pole, the barrel, the drum, the Geneva stop, the barrel-connecting device, the electromagnetic device and the switch which is closed when the trolley-pole is free: the drum-holding device consisting of a detent-lever adapted to engage with a tooth on the drum, the lever-control- 130

ling contacts in the electromagnetic circuit and a cam on the locking-wheel of the Geneva stop which holds the detent-lever from engagement with the tooth on the drum and 5 holds the contact-lever in its off position except when the drum is fully wound up; substantially as described.

10. In combination with means adapted to pull down a trolley-pole, and an electromagnetic device for releasing said means: a switch, 10 adapted to close the circuit of said device, and carried at a point of flexure in the trolley-pole the two contacts of which switch are on op-

posite sides of the point of flexure, and a spring adapted when the trolley-pole is free 15 to straighten the trolley-pole and bring the two contacts together; substantially as described.

In witness whereof I have hereunto set my hand in the presence of two subscribing witnesses.

DANIEL RICHARD WALLWORK HARDMAN.
